UNITED STATES PATENT OFFICE.

EDWARD E. ROBERTS, OF RED BANK, NEW JERSEY.

STEAM-GENERATOR.

SPECIFICATION forming part of Letters Patent No. 371,710, dated October 18, 1887.

Application filed July 12, 1887. Serial No. 244,054. (No model.)

To all whom it may concern:

Be it known that I, EDWARD E. ROBERTS, of Red Bank, in the county of Monmouth and State of New Jersey, have invented a new and 5 useful Improvement in Steam-Generators, of which the following is a specification.

My invention relates more particularly to steam-generators of comparatively small size, such as are usually employed for launches and 10 other small steam-vessels; but the invention may, if desired, be embodied in generators of larger size for other purposes.

Important objects of my invention are to provide a generator which will generate steam 15 rapidly by reason of a very effective circulation, which will generate dry steam and avoid priming, and which will also afford proper opportunity for the separation of steam from the water; also, to afford provision for blowing off the generator a little at a time, as sediment may collect in suitable receptacles or 20 pockets provided therefor, and to avoid the necessity of blowing off the boiler entirely, and thus suspending the generation of steam at any 25 time.

My improved generator is constructed largely of pipes or tubes, and a more clear idea of the invention may be obtained by first giving a brief description of the parts thereof. In 30 what I now consider a desirable form of the invention it comprises a steam and water drum which is approximately horizontal, and pipes which descend from and communicate with opposite ends of this drum. At what are approximately the four corners of the generator 35 there are four upright pipes or water-columns. The two pipes which are at each end of the drum are connected at their upper ends by a cross-pipe which communicates with the 40 end of the drum, and those pipes which are upon each side of the generator are connected near their lower ends by a water-distributer. A number of upright coils or pipes connected by return-bends are arranged beneath the 45 drum and spring at their lower ends from the horizontal water-distributers, and at their upper ends communicate with the drum, and these upright coils form in effect the crown of the fire-box. A rapid circulation takes place 50 from the drum downward through the larger pipes to the horizontal water-distributers, and thence upward through the smaller upright

coils to the drum. I also provide adjacent to the drum a system of feed-water-heating coils on one or each side of the drum, and through 55 which the feed-water passes before it enters the drum, whereby it is preliminarily heated, and I provide on opposite sides of the fire-box and adjacent to the downwardly-extending end portions of the upright coils two dry coils or 60 superheating-coils, through which the steam passes and is superheated after it leaves the water and steam drum. The four descending pipes, which provide for downward circulation, may each of them be prolonged slightly 65 below the horizontal water-distributer and be each provided with a blow-off pipe, so that at any time a portion of the water and the sediment in the generator may be blown off without allowing the fire to go down or emptying 70 the generator, and without any cessation of its operation in producing steam.

The generator may have a ledge of angle-iron constructed around it and the casing, or 75 cover of sheet metal which incloses the several parts of the generator, may be fitted, by an asbestos packing or otherwise, upon this angle-iron ledge and may have a smoke-stack at the top.

The invention hereinabove briefly described 80 consists in novel combinations of parts, herein-after particularly set forth, and pointed out in the claims.

In the accompanying drawings, Figure 1 is a front elevation of a generator including my 85 invention, the front of the external casing being removed. Fig. 2 is a side elevation thereof, including a sectional view of the casing. Fig. 3 is a transverse section—say upon about the plane indicated by the dotted line *xx*, Fig. 90 2. Fig. 4 is a longitudinal section of the generator—say upon about the plane indicated by the dotted line *yy*, Fig. 1; and Fig. 5 is a detail view showing a portion of the drum and one of the upright coils as having its approxi- 95 mately horizontal members which form the crown of the fire-box slightly inclined in a direction transverse to the length of the drum.

Similar letters of reference designate corresponding parts in all the figures.

My generator is supported upon two horizontal bearers or timbers, A, if desired, and above them is placed an ash-pan, B. At about 100 what are the four corners of the generator pipes

C rise at each end thereof and are connected by a cross-pipe, C', the same arrangement of pipes C C' being at each end of the generator, and the cross-pipes C' are connected or 5 communicate at c with the steam and water drum D, as best shown in Figs. 3 and 4. At each end of the generator a dead-plate, e, extends across from side to side thereof, and the grate-bars, of which there are two lengths, e', 10 are raised upon suitable bearers, e².

It will be observed that in small generators like that shown in the drawings the grate e' fills the entire length of the generator.

Between the larger pipes, C, which are at 15 each side of the generator, extends a horizontal water-distributer, C², as best represented in Fig. 3, and each water-distributer C² communicates with the larger pipe, C, which descends at each side of the generator. The 20 grate e' extends across from one water-distributer C² to the other, as best shown in Fig. 3.

As a principal steam-making portion of the boiler, upright coils or pipes connected by return-bends, so as to form what are practically 25 coils E, are arranged closely together side by side above the grate, and form in effect the crown of the fire-box. Each of these coils E has a downwardly-extending leg or portion, e³, which communicates with one or the other 30 of the water-distributers C², and at its upper end the branch e⁴ communicates with the steam and water drum slightly below the water-line thereof. The coils E spring alternately from opposite water-distributers C² and communicate 35 alternately with the drum D on opposite sides of its vertical center—that is to say, one coil E springs from the water-distributer C² at the left hand of Fig. 3 and communicates with the drum D on the right-hand end of its center, while the coils E which are on opposite sides of the one named spring from the 40 water-distributer C² at the right hand of Fig. 3 and communicate with the drum D on the left hand of its center. The coils E are exposed 45 more directly to the intense heat of the fire than the descending pipes C, and, both by reason of this more intense exposure to heat and by reason of the smaller size of the coils E, a rapid circulation downward takes place 50 through the pipes C and into the water-distributers C², while from such water-distributers a rapid circulation takes place upward through the coils E to the drum D.

I have here represented the operative parts 55 of the generator as inclosed by a casing, F, which may be of sheet-iron or other metal, and which has a covering, f, of asbestos or other known non-heat-conducting material, and this casing F may be slipped within the angle- 60 iron ledge F', which extends around the entire generator and, as here shown, is about on a level with the water-distributers C². At the top the casing F has a smoke-stack, F², which is inserted within a socket, f', and packed 65 with asbestos or other suitable material, f². This smoke-pipe F² may be readily removed

when its height would be in the way of navigation.

At opposite sides of the drum D, I have represented a mass of coils or pipes connected 70 by return-bends, each body of pipes being designated by the letter G. The two masses of coils or pipes are connected at the points g, one with one end of the drum D and the other with the other end thereof, and the opposite ends of both said coils are connected together by a pipe, g', with which the feed branch g² communicates; hence the feed-water which is being pumped into the pipe g' will circulate completely through the two coils G before it 80 is delivered into the drum D, and consequently the feed-water will be highly heated before it enters the drum.

In addition to the pipes above described, I have represented at each side of the generator, 85 and just outside the downwardly-extending legs e³ of the coils E, a dry coil, H, which is employed for superheating steam. The drum D has at its upper part a longitudinal pipe, H', which extends from end to end thereof 90 and is perforated, preferably, in its top, and from opposite ends of the pipe H' pipes h lead to the dry or superheating coils H, and from the ends of said coils and through the branches h' the steam escapes for use in the engine or 95 elsewhere, both said branches h' being coupled by a suitable pipe. (Not here shown.) By this arrangement of dry coils or superheating-coils H heat which would otherwise be wasted in the generator is employed for raising the 100 temperature of the steam generated or superheating it to a high degree before it makes its escape for use in the engine or elsewhere. The downwardly-extending pipes C are prolonged somewhat below the horizontal water- 105 distributors C², so as to form pockets or receptacles for sediment, and from the lower end of each of these pipes C leads a blow-off pipe, c', provided with suitable valves, c²; hence it follows that these sediment-pockets and the necessary small quantity of water may be blown off at any time without the necessity of blowing off all the water in the boiler or suspending its operation.

A water-column, I, provided with a suitable 115 water-gage glass, i, and gage-cocks i', may be connected by a pipe, i², with the steam-space of the drum D, and by a pipe, i³, with one of the horizontal water-distributers C², and affords opportunity for ascertaining the exact 120 level of water in the generator at any time. The water-column I may be surmounted by a steam-gage, i⁴.

It will be seen from the above description that I provide a generator which is safe and 125 which will be a very rapid producer of dry steam. The generator will not be likely to choke up in using different kinds of fuel, and ample provision is afforded for blowing off at intervals without discharging any considerable quantity of water from the generator.

Although I do not confine myself to any ex-

act proportions for the various parts of my generator, a statement of the dimensions which may be employed to make an operative apparatus may be advantageous. In an operative 5 generator I make the upright coils E of one-inch pipe, with a steam-drum, D, fifteen inches in diameter by about the length of the boiler. I make the four vertical pipes C about three inches in diameter and the horizontal water- 10 distributors C² of the same size. I make the feed-water coils G of one-half-inch pipe, and I make the dry coils or superheating-coils H of one-and-one-fourth-inch pipe.

To facilitate the upward circulation of water and steam through the coils E, their lateral parts, which pass to and fro across the generator may be slightly inclined, as represented in Fig. 5, although they may in some cases be approximately horizontal, as represented in Figs. 1 and 3.

The arrangement of the dry or superheating coils H at the sides of the fire-box and transversely to the planes of the upright coils E is very important, as they do not then shield the 25 coils E from the direct and most intense heat of the fire, and they themselves are not so liable to be burned out speedily. I therefore do not seek to include in my invention dry or superheating coils arranged below the coils or 30 tubes which extend across immediately above the fire and in the same plane with said coils or tubes.

What I claim as my invention, and desire to secure by Letters Patent, is—

35 1. The combination, with a steam and water drum and pipes depending at opposite ends thereof and on opposite sides of the fire-box, the pipes at each end having a cross-connection by which they communicate with the 40 drum, of the distributors C², each connecting the depending pipes which are on the one side of the fire-box and the coils E, springing from the opposite distributors alternately, forming the crown of the fire-box and communicating at their upper ends with the drum, 45 substantially as herein described.

2. The combination, with a steam and water drum and pipes depending from the ends thereof, of hot-water distributors, each con-

nected the depending pipes which are on 50 one side of the generator, upright coils connected at their lower ends with the distributors and at their upper ends with the drum and forming the crown of the fire-box, and dry or superheating coils arranged transversely to 55 the planes of the upright coils and on opposite sides of the fire-box, leaving the coils which form the crown of the fire-box fully exposed to the fire, substantially as herein described.

3. The combination, with a base or foundation, of the stand-pipes C, supported thereon, and the steam and water drum, the pipes at each end of the drum being connected by a cross-pipe which connects with and supports the drum, the horizontal distributors connecting the stand-pipes, which are on opposite sides of the generator, the grate arranged between said distributors, and the upright coils E, leading from the distributors to the drum and forming the crown of the fire-box, substantially as herein described.

4. The combination, with the steam and water drum D, the downward pipes C, and distributors, of the upright coils E, connecting the distributors and drum and forming the 75 crown of the fire-box, the feed-water-heating coils G, and the superheating-coils H, the ledge of angle-iron F' surrounding the lower portion of the generator, and the case or cover 80 inclosing the generator and fitting on said ledge, substantially as herein described.

5. The combination, with a steam and water drum, the water-columns or stand-pipes C, which communicate at their upper ends with the drum, and water-distributors C², connecting the stand-pipes near but above their lower ends, thereby forming sediment-pockets in the lower ends of the stand-pipes, of the return-coils E to the drum, and blow-off connections leading from the sediment-pockets in the 90 stand-pipe below their connection with the water-distributors C², substantially as herein described.

EDWARD E. ROBERTS.
